Primary Examiner — Robin V Webster(74) *Attorney, Agent, or Firm* — Cahn & Samuels, LLP(57) **CLAIM**

The ornamental design for a flow conditioner, as shown and described.

DESCRIPTION

FIG. 1 illustrates a rear perspective view of a flow conditioner having 1) a flange on a first side; 2) an outer ring of holes on the first side, said outer holes extending to a second side; 3) an inner ring of holes on the first side recessed from the outer ring of holes, said inner holes extending to the second side; and 4) a central hole recessed on the first side within the inner ring of holes and opening on the second side.

FIG. 2 illustrates a front perspective view of a flow conditioner of FIG. 1.

FIG. 3 illustrates a front view of the flow conditioner of FIG. 1.

FIG. 4 illustrates a rear view of the flow conditioner of FIG. 1; and,

FIG. 5 illustrates a side view of the flow conditioner of FIG. 1.
